LADY'S SHOE

Edith Forschner, New York, N. Y.

Application October 3, 1950, Serial No. 12,430

Term of patent 3½ years

(Cl. D7—7)

To all whom it may concern:

Be it known that I, Edith Forschner, a citizen of the United States, residing in New York city, in the county of New York and State of New York, have invented a new, original, and ornamental Design for a Lady's Shoe, of which the following is a specification, reference being had to the accompanying drawing, forming a part thereof.

In the drawing:

I claim:

The ornamental design for a lady's shoe, as shown.

EDITH FORSCHNER.
